(57) **CLAIM**

The ornamental design for an embossed graph paper, as shown and described.

DESCRIPTION

FIG. 1 is a front perspective view of an embossed graph paper showing my new design;

FIG. 2 is a front elevation view thereof;

FIG. 3 is a rear elevation view thereof;

FIG. 4 is a top plan view thereof, the bottom plan view being a mirror image thereof;

FIG. 5 is a right side elevation view thereof, the left side elevation view being a mirror image thereof;

FIG. 6 is an enlarged detail of the circumscribed 6-6 area of FIG. 5; and,

FIG. 7 is an enlarged detail of the circumscribed 7 area of FIG. 5.

The broken line showing portions of the embossed graph paper is included for the purpose of illustrating environmental structure and forms no part of the claimed design.
